Application May 10, 1937, Serial No. 141,816

15 Claims. (Cl. 197—17)

This invention relates to improvements in typewriters and more particularly to a novel automatic action which is substantially noiseless in operation.

5 The following are some of the objects of the invention:

1. A typewriter action in which the finger keys are so connected with the type bars that each bar may complete its printing cycle before the 10 particular key used for actuating the same has reached its fully depressed position.

2. A typewriter action which may be so adjusted as to cause automatic action and printing at any desired depression of the finger key.

15 3. A typewriter action which can be instantly adjusted and re-adjusted to print with any degree of intensity from light to heavy.

4. A typewriter action which when adjusted for a short stroke by pressure will, as a matter of 20 course, print quietly.

5. A typewriter action of independent but co-operative elements so arranged that the energy or power used is not controlled by the force or manner of striking the finger key but by a spring 25 or its equivalent which effects the final movement of the type bar into contact with the platen.

6. A typewriter action which by having independent elements makes possible a separate adjustment of the finger key to all gradations of touch from light to heavy without affecting the 30 printing.

7. A typewriter action in which the type bar is finally moved into contact with the platen by a 35 spring-actuated structure or the like instead of by manual power.

8. A typewriter action in which the type bar is moved into a position close to the platen by 40 pressing the finger key and is then moved the remaining distance by other power means, the power of which is immediately restored after printing.

9. A typewriter action in which the movement 45 of a finger key will cause energy to be stored in a spring or the like which subsequently functions to instantaneously and automatically force the type bar against the platen, whereby all type bars of the machine may be made to print uniformly regardless of whether the touch on the 50 keys is heavy or light.

10. A typewriter action of the foregoing character having means for adjusting the strength or power of the energy-storing means so that a large 55 or small number of carbon copies may be made substantially regardless of the touch exerted on the finger keys.

11. A typewriter action of the above kind having auxiliary means for varying the yielding 60 characteristics of the finger keys to permit the

machine to be conditioned to accord with the touch of any individual.

The invention in its several aspects may be better understood and comprehended in connection with a description of certain embodiments 5 thereof, and by reference to the accompanying drawings which illustrate the same. The indicated embodiments are given for illustrative purposes only, and it is to be understood that the arrangements shown and the details of construction illustrated may be widely varied without departing from the scope of the invention.

In the drawings:

Figs. 1 to 4 inclusive, are longitudinal, vertical, sectional views of a typewriter structure showing our action in various positions and with the finger key lever so connected with the type bar or type carrier that the key lever must rise when the type bar is being retracted.

Fig. 5 is an enlarged similar view of a portion 20 of the mechanism but showing the key lever unlatching means ready to operate to allow the key lever to remain depressed while the type bar is being retracted.

Fig. 6 is a view similar to Fig. 5 showing the 25 key lever latch released.

Fig. 7 is a horizontal, sectional view of a detail taken on the line 7—7 of Fig. 5.

Fig. 8 is a transverse sectional view of a detail taken on the line 8—8 of Fig. 6. 30

Fig. 9 is a sectional view of another detail taken on the line 9—9 of Fig. 6.

Fig. 10 is a side elevation of another embodiment of the invention and showing the parts in normal or inactive position.

Fig. 11 is a similar view of the same embodiment, but showing the parts in different positions after the key lever has been depressed to a certain degree. 35

Typewriters generally, depend upon the momentum set up by the operator's fingers to do the printing or to exert the power necessary to cause the final impact of the type bar to leave an inked impression on the paper. In the present invention, the printing action does not depend on momentum supplied by the operator's fingers, but upon spring power or its equivalent. In furnishing such spring power or the like to accomplish the printing, the invention supplies means by which the power thus exerted is renewed or restored ready for the next action of the type bar. This renewal of power is of great importance. 40 In accordance with the invention, the power of the spring or the like is employed to print, but such power is instantaneously restored after printing. The result is that an operator can strike a key quickly, as is the case with all other typewriters, or press downward as slowly as possible, and yet the type bar automatically and without the exertion of momentum will fully 45

cycle and perform its function of printing. In other words, as soon as the key has been depressed, whether swiftly or slowly, to a predetermined degree, the spring or the like will automatically complete the movement of the type bar into contact with the platen, and when the type bar is returned to idle position, the power of the spring or the like will be restored or made ready for a succeeding cycle of the type bar.

10 Referring to Figs. 1 to 4 inclusive, 10 designates a typewriter frame; 11, a platen; 12, a platen carriage; and 13, inking mechanism. These elements may be of any preferred construction as they simply cooperate with our improved action.

14 designates a type member which for the purpose of the present invention may be a lever or bar having its lower end pivotally connected to the frame as shown at 15 and provided at its upper end with a type face 16 designed to force the ribbon against paper arranged about the platen.

17 designates a finger key element which may be a lever having its rear end pivotally connected to the frame as shown at 18 and provided at its forward end with a key 19.

In accordance with the present invention the means 14 and 17 are connected by mechanism including a toggle, so mounted as to move the type face 16 toward the platen until the toggle assumes a substantially straight or dead center position, at which time a portion of the mechanism will be released by a latch and the toggle and type member will be moved instantaneously into contact with the platen by energy-storing means, such as a spring, that is activated by the movement of the type lever.

In the embodiment of the action illustrated in Figs. 1 to 9 inclusive, the toggle comprises links 20 and 21 pivotally connected together at 22. The link 20 is pivotally connected at its rear end to the type bar, and the link 21 is pivotally connected at 24 to one arm 25 of a three-armed lever that is pivotally supported at 26 by the frame of the machine. The three-armed lever has depending arms 27 and 28; the former being connected by a coil spring 29 to one arm 30 of a bell crank lever, pivotally mounted at 31 on a plate 32 which may be moved forwardly and backwardly, by means hereinafter described, to adjust the tension of the spring 29.

A link 33 pivotally connects the bell crank 34 to a lever 35 arranged substantially parallel to the key lever and pivotally mounted at 36 on the frame. The levers 17 and 35 are latched together by a detent 37 having a hook 38 engaging a complimentary hook 39 on the lever 35. The detent is pivotally mounted at 40 on the lever 17 and it has a cam-faced tail 41 for a purpose hereinafter described. Any suitable means, such as a spring 42, which connects the parts 37 and 17, may be employed to hold the detent 37 in latching position.

A spring 43 connects the lever 17 to the frame for yieldingly holding said lever in normal position.

Another spring 44 is employed to hold the lever 35 in normal position and this spring may be connected to any suitable means employed to adjust its tension. For example, it has one of its ends secured to a bell crank lever 45 which is pivotally mounted on the frame at 46, and may be swung by means hereinafter described.

A relatively long link 47 has its lower end pivotally connected to the lever 35 and its upper end

pivots connected to one end of the toggle link 21, and it is therefore obvious that if the link is moved downwardly, the toggle link 21 will pivot at 24 and move the other toggle link with it, and of course, this results in movement of the 5 key face 16 toward the platen.

The three-armed lever is normally latched to prevent the pivot 24 from moving toward the platen but when the latch releases the lever, said pivot can move toward the platen with the result that the toggle (in straightened position) can force the type face 16 into contact with the ribbon. Said latch may consist of a bell crank lever 49. A coil spring 50 connects one arm of the bell crank lever with the frame and acts to 10 yieldingly hold its other arm 49 in contact with a stop 51. When the last-mentioned arm is in normal position it cooperates with the upper end 52 of the three-armed lever to prevent the latter from swinging in a clockwise direction. However, if the link 47 moves downwardly and the toggle link 21 is swung in a counterclockwise direction, a cam 53 integral with the toggle link will come into contact with the lever 49 and turn the latter to a position where it will no longer obstruct the movement of the three-armed lever, and at such time the spring 29 will function to instantaneously move the type face into contact with the platen.

It will be noted that the arm 28, when the parts are in normal position, engages a grooved member 54 on the lever 35 which also acts to prevent movement of the three-armed lever in a clockwise direction. However, the lever 35 moves downwardly with the key lever and at such time the member 54 will be moved out of engagement with the arm 28. When the lever 35 is moved upwardly, of course, the member 54 will engage the arm 28 and act to return the three-armed lever to normal position.

The operation may be readily understood by viewing Figs. 1 to 4 inclusive. With the parts in normal position as shown in Fig. 1, if the key 19 is depressed, the detent 37 will act to swing the lever 35 downwardly. This will result in movement of the parts 33, 34 and 30 and the tensioning or storing up of energy of the spring 29. At the same time the long link 47 acts to bring the toggle 21, 20 into a substantially straight position, as illustrated in Fig. 2. At such time the type face 16 has been brought into close proximity to the platen but slightly spaced therefrom. Further depression of the key 19 causes the cam 53 to release the latch lever 49 with the result that the energy-storing means or spring 29 now acts instantaneously to shift the pivot 24 of the toggle as well as the toggle toward the platen so that the type face immediately strikes the platen a sharp blow.

When the key 19 is released or pressure is removed from the same, the springs 43 and 44 function to return the levers 17 and 35 to normal position, and as the latter lever rises it engages the arm 28 and moves the three-armed lever in a counter-clockwise direction about its pivot 26 to restore that lever to normal position. Then the spring 50 acts to re-set the latch lever 49.

From the foregoing it will be understood that depression of key 19 simply acts to store energy in the spring 29 and to set the type lever 14 in "cocked" or "ready" position at which time energy stored in the spring 29 is released and such energy-storing means functions to force the type face against the platen.

In such a construction the type levers will strike

the platen with equal force regardless of the force exerted on the keys and this results in uniform and quiet typing.

The degree of energy stored in the spring 29 can be varied so as to take care of more or less carbon copies. For example, as shown in Fig. 8, the plate 32 which carries the bell crank lever 34, 30 slides in a guide slot 55 in the frame. The carriage or plate 32 can be adjusted in its guide slot 10 by any suitable means. For example, it may be provided with a threaded pin 56 which is fixed to the carriage and extends through the front portion 57 of the frame. A hand nut 58 is swiveled in the front portion of the frame and has threaded engagement with the pin 56, and it is manifest that turning of the nut will result in forward or backward movement of the carriage 32.

The means for adjusting the tension of the spring 44 may be the one illustrated specifically in Fig. 7. Here it will be noted that one arm 59 of the bell crank lever 45 extends into an annular groove 60 in a screw member 61. The latter has threads 62 at its inner end, engaging a nut 63 that is fixed to the frame. The screw member also extends through the front portion 57 of the frame and is provided with a handle or knob 64. If the screw member 61 is turned it will function to swing the bell crank 45 about its pivot 46 with the result that the spring 44 is tensioned to the degree desired. A stop pin 65 on the frame cooperates with an annular groove 66 on the screw member to limit adjustment of the latter.

By adjusting the tension of the spring 44 the machine may be conditioned to take care of a heavy or light touch of individual typists.

The mechanism as described, necessitates return of the key lever to normal position in order to restore the type lever to normal position but by means of the feature now described, the type lever will return to normal position even though the key lever is held depressed or pressure is not released from the same. This is best illustrated in Figs. 5, 6 and 9. In these figures it will be noted that the cam tail 41 can cooperate with a slidable pin 67, which acts to obstruct the downward movement of the detent. It will be noted when the key lever 17 is depressed from normal position (Fig. 5), the cam tail contacts with the pin 67 with the result that the detent is moved in a counter-clockwise direction as shown in Fig. 6. Of course, this results in releasing of the hook 39 by the hook 38 of the detent. Consequently the spring 44 will act to restore the parts to normal position even though the key lever is held down in the position shown in Fig. 6. However, as soon as the key lever is released, its spring 43 will lift it and the cam faces of the hooks 38 and 39 will co-act to guide the hook 38 into latching position.

The pin 67 may be moved into projected or retracted position by means of a lever 68 which is pivotally connected to the pin as shown at 69. The lever is pivotally mounted on the frame as shown at 70 and it has a handle or knob 71 arranged at the front portion of the machine. Of course, when the lever is swung in the proper direction the pin 67 will be retracted so that it will not interfere with the detent 37.

The mechanism is provided with suitable buffers 72, 73, 74, 75 and 76 to cushion the movement of the parts and to substantially eliminate noise.

In the modification shown in Figs. 10 and 11,

the frame of the machine is shown at 10a and the platen is indicated as 11a.

A type bar 12a is pivotally supported by the frame of the machine as shown at 13a and is provided at its upper end with a type face 14a. 5 A toggle link 15a has one of its ends pivotally connected at 16a to the type lever, and is pivotally connected at its opposite end to a second toggle link 17a, the latter being pivotally connected at 18a to the upper arm 19a of a two- 10 armed lever that is pivotally supported at 20a on the frame of the machine. The two-armed lever forms a shifting pivot means for the toggle so that the latter may be bodily moved toward the platen when the toggle is in a zone of substantially dead center, i. e., when the toggle is 15 in substantially straight position.

A normally extended or expanded spring 21a connects the upper end of the arms 19a to a forwardly and backwardly adjustable member 20 20 22a, which is on the frame and held in adjusted positions by screws 22b. The spring, of course, acts to move the toggle bodily toward the platen when the arm 19a is released by a latch 23a. The latch is pivotally supported at 24a on the 25 frame of the machine and it is yieldingly held against a stop 25a by a spring 26a. A nose or cam 27a on one of the toggle links functions to raise the latch to releasing position when the link 17a is swung in a counter-clockwise direction by the downward movement of a link 28a. This link is pivotally connected at 29a to one end of the toggle link 17a, and is pivotally connected at its opposite end as shown at 30a, to a lever 31a that has one of its ends pivotally supported at 32a by the frame of the machine. The opposite end of this lever is yieldingly supported by a spring 33a, which has greater strength than the spring 21a. A cam 34a on the lever cooperates with the second arm 35a of the 40 two-armed lever for the purpose of restoring the power of the spring 21a and returning the structure to latched position.

The finger key lever 36a is shown pivotally supported at 37a by the frame of the machine 45 and it is yieldingly held in raised position by a spring 38a. A hook detent 39a is pivotally mounted on the key lever and cooperates with a hook 40a on the front end of the lever 31a. When the key lever is depressed, the detent 50 causes lowering of the lever 31a until the tail 41a of the lever contacts an abutment 42a which causes the detent to swing about its pivot and release the hook 40a. As soon as the release occurs, the spring 33a immediately lifts the front 55 end of the lever 31a. A spring 43a and cam faces on the detent and hook cooperate to cause the detent to again engage the hook 40a when pressure is released from the key.

In the operation of this form of the invention, when the key lever 36a is depressed, the detent 39a will pull down the lever 31a so as to release the cam 34a from the arm 35a. At the same time the link 28a swings the toggle link 17a in a clockwise direction which tends to 60 straighten the toggle and to move the type lever toward the platen. Just before the type bar reaches the platen, the cam 27a will release the latch 23a and at such time the extended spring 21a will move the type face 14a instantaneously 70 into contact with the platen. At this time the lever 36a will have been depressed to the point where the detent releases the hook 40a and consequently the spring 33a will come into action to immediately lift the lever 31a. As this lever 75

rises, the cam 34a will engage the arm 35a and swing the two-armed lever in a counter-clockwise direction while the link 28a is restoring the toggle to collapsed position. Of course, when the two-armed lever has been swung far enough, the spring 26a will bring the latch 28a again into latching position. Then if the pressure is removed from the key lever, it will rise under influence of the spring 38a and the detent will again come into engagement with the hook 40a.

Any suitable means such as shown in Figs. 1 to 6 inclusive, may be employed for adjusting the tension of the springs 21a and 33a.

It will be observed that the spring 29 in Figs. 1 to 9 inclusive, and the spring 21a in Figs. 10 and 11 function differently. In Figs. 1 to 9, the spring 29 may normally be in a contracted or non-extended condition, and it is extended when the finger key lever is depressed. The spring 21a, however, in Figs. 10 and 11 is normally in an extended position and when the lever 31a rises after a printing cycle, the cam 34a cooperates with the lever arm 35a to cause extension of the spring 21a when the structure is restored to latched condition.

It is obvious that means other than the spring 33a may be employed for restoring the power of the spring 21a and returning the structure to latched position. For example, we may employ an electro magnet which would be energized about the time that the type face strikes the platen and would be de-energized when the parts have returned to latched position.

With reference to the quiet action of the mechanism we may state that the greatest noise in typewriter operation is caused by the impact of the type bar on the paper and the platen. In the present invention, the actual typing structure is held back by a latch until the toggle reaches a substantially straight position, when the latch is released to allow the type bar to fly against the platen. If the type bar were permitted to fly the entire distance (which is about two and a half inches from rest position to the platen) it might make as much noise as any of the modern noisy typewriters. However, in the present case, the type bar is held back until the toggle is substantially straightened out. Naturally, as the toggle straightens out, it theoretically stops, so that the action of this bar is to stop for the fraction of an instant before it prints, and, as the distance it flies is only a fraction of an inch, it decreases the noise to just that extent.

Many modifications of the invention will be apparent to those skilled in the art, and since the foregoing disclosure has been given by way of example, for clearness and understanding, no unnecessary limitations should be understood and the appended claims should be construed as broadly as the state of the art permits.

What we claim and desire to secure by Letters Patents is:

1. In a typewriter, in combination, a platen, type means movable toward and away from the platen, key means, means operatively connecting the type means and key means for causing the type means to move into close proximity to the platen when the type means is depressed, a spring cooperating with the connecting means to instantaneously drive the type means into contact with the platen when the key means has been depressed to a predetermined position, and other means cooperating with the connecting means to prevent the spring from acting until the key

means has been depressed to a predetermined position.

2. In a typewriter, in combination, a platen, type means movable toward and away from the platen, key means, a toggle operatively connected to said type means and key means, shiftable pivot means for said toggle normally maintaining the toggle in such position that said type means upon application of pressure on the key means will be advanced within close proximity of the platen as the toggle travels from a collapsed position to a zone of substantially dead center, and an energy-storing means for shifting the toggle pivot means and toggle toward the platen when the toggle reaches said zone so as to move said type means against said platen.

3. In a typewriter, in combination, a platen, type means movable toward and away from the platen, key means, a toggle operatively connected to said type means and key means, shiftable pivot means for said toggle normally maintaining the toggle in such position that said type means upon application of pressure on said key means will be advanced within close proximity of the platen as the toggle travels from a collapsed position to a zone of substantially dead center, and a spring cooperating with said shiftable pivot means for instantaneously shifting the toggle pivot means and the toggle toward the platen when the toggle reaches said zone whereby the type means is driven against the platen.

4. In a typewriter, in combination, a platen, type means movable toward and away from the platen, key means, a toggle operatively connected to said type means and key means, shiftable pivot means for said toggle normally maintaining the toggle in such position that said type means upon application of pressure on said key means will be advanced within close proximity of the platen as the toggle travels from a collapsed position to a zone of substantially dead center, latching means for preventing movement of the shiftable pivot means toward the platen until the toggle reaches said zone, means for causing the latching means to release the shiftable pivot means when the toggle reaches said zone, and energy-storing means for shifting the toggle pivot means and toggle instantaneously toward the platen as the toggle reaches said zone for causing the type means to strike the platen.

5. In a typewriter, in combination, a platen, a pivoted type bar having a type face at one end thereof movable toward and away from the platen, key means, a toggle operatively connected to said type bar and key means, shiftable pivot means for said toggle normally maintaining the toggle in such position that said type face upon application of pressure on said key means will be advanced within close proximity of the platen as the toggle travels from a collapsed position to a zone of substantially dead center, and a spring cooperating with the shiftable pivot means for instantaneously moving said pivot means and toggle toward the platen when the toggle reaches said zone whereby the type face is caused to strike the platen.

6. In a typewriter, in combination, a platen, type means movable toward and away from the platen, key means, a toggle operatively connected to said type means and key means, shiftable pivot means for said toggle normally maintaining the toggle in such position that said type means upon application of pressure on said key means will be advanced within close proximity of the platen as the toggle travels from a collapsed

position to a zone of substantially dead center, a spring cooperating with the shiftable pivot means for instantaneously moving said pivot means and toggle toward the platen when the toggle reaches said zone whereby the type means is caused to strike the platen, and means for adjusting the tension of said spring.

7. In a typewriter, in combination, a platen, type means movable toward and away from the platen, key means, means operatively connecting the type means and key means for manually moving the type means into close proximity to the platen when the key means is depressed to a predetermined position, power means cooperating with said connecting means for instantaneously driving the type means into contact with the platen when the key means is depressed beyond such position, and means operated by and operatively connected with the key means for utilizing movement of the key means to store power in the power means.

8. In a typewriter, in combination, a platen, type means movable toward and away from the platen, key means, means operatively connecting the type means and key means for manually moving the type means into close proximity to the platen when the key means is depressed to a predetermined position, power means energized by movement of the key means and cooperating with said connecting means for instantaneously driving the type means into contact with the platen when the key means is depressed beyond such position, and latching means cooperating with the power means to prevent functioning of the power means until the type means has been moved into close proximity with the platen.

9. In a typewriter, in combination, a platen, type means movable toward and away from the platen, key means, means operatively connecting the type means and key means for first moving the type means into close proximity to the platen and then substantially halting the type means when the key means is manually depressed, and power means operatively connected to said connecting means for instantaneously driving the type means into contact with the platen when it has been brought into close proximity thereto by the key means.

10. In a typewriter, in combination, a platen, type means movable toward and away from the platen, key means, means operatively connecting the type means and key means for first moving the type means into close proximity to the platen and then substantially halting the type means when the key means is manually depressed to a predetermined position, and power means operatively connected to said connecting means for instantaneously driving the type means into contact with the platen only when the key means is depressed beyond such position.

11. In a typewriter, in combination, a platen, type means movable toward and away from the platen, key actuated means for moving the type means into close proximity to the platen, power means controlled by the key means and operatively connected with the type means for driving the type means into contact with the platen after the type means has been moved toward the platen by the key-actuated means, and independent power means for restoring the power of the power means and returning the type means to normal or retracted position after the type means has contacted with the platen.

12. In a typewriter, in combination, a platen, type means movable toward and away from the platen, key means, means operatively connecting the type means and key means for first causing the type means to move into close proximity to the platen and then momentarily halt when the key means is depressed, and energy-storing means co-operating with the connecting means to instantaneously drive the type means into contact with the platen only when the key means has been depressed to a predetermined position.

13. In a typewriter, in combination, a platen, type means movable toward and away from the platen, a key element, connecting means operatively connecting the type means and key element for causing the type means to move in a path into close proximity to the platen when the key element is depressed to a predetermined position, an energy-storing device operatively connected with one of said means to rapidly drive the type means in said path into contact with the platen when the key element reaches such predetermined position, retaining mechanism associated with the energy-storing device to prevent the latter from acting upon said type means until the connecting means has reached a predetermined position, and a contrivance controlled by one of said means and engageable with the retaining mechanism to release the latter to cause the energy-storing device to act.

14. In a typewriter, in combination, a platen, type means movable toward and away from the platen, a key element, connecting means operatively connecting the type means and key element for causing the type means to move in a path into close proximity to the platen when the key element is depressed to a predetermined position, an energy-storing device operatively connected with the connecting means to rapidly drive the type means in said path into contact with the platen when the key element reaches such predetermined position, retaining mechanism associated with the energy-storing device to prevent the latter from acting upon said type means until the connecting means has reached a predetermined position, and a contrivance controlled by said connecting means and engageable with the retaining mechanism to release the latter to cause the energy-storing device to act.

15. In a typewriter, in combination, a platen, type means movable in a curvilinear path toward and away from the platen, a key element, connecting means operatively connecting the type means and key element for causing the type means to move in said path into close proximity to the platen when the key element is depressed to a predetermined position, an energy-storing device operatively connected with the connecting means to rapidly drive the type means into contact with the platen when the key element reaches such predetermined position, latching mechanism engageable with the energy-storing means to prevent the latter from acting upon said type means until the connecting means has reached a predetermined position, and means mounted on said connecting means and engageable with the latching mechanism to release the latter to cause the energy-storing device to act upon the connecting means.
